to Superba Cravats, Rochester, N. Y., a co-partnership

Application March 3, 1947, Serial No. 137,306

Term of patent 14 years

(Cl. D92—1)

To all whom it may concern:

Be it known that I, Hyman W. Lewine, a citizen of the United States, residing at New York, in the county of New York and State of New York, have invented a new, original, and ornamental Design for Textile Fabric or Similar Article, of which the following is a specification, reference being had to the accompanying drawing, forming part thereof.

The figure is a view of a piece of textile fabric, showing the design.

The design unit is outlined by broken lines. Said unit repeats over the fabric as indicated by the extensions beyond the unit boundaries.

I claim:

The ornamental design for a textile fabric or similar article, substantially as shown and described.

HYMAN W. LEWINE.
